US00D531580S

(12) **United States Design Patent** (10) **Patent No.:** **US D531,580 S**
(45) **Date of Patent:** **** Nov. 7, 2006**

(54) **CONNECTOR**

(75) Inventors: **Atsushi Nishio**, Tama (JP); **Takashi Kawasaki**, Tama (JP); **Masashi Ouchi**, Tama (JP); **Takahiro Shimoyama**, Tama (JP)

(73) Assignee: **Mitsumi Electric Co., Ltd.**, Tokyo (JP)

(**) Term: **14 Years**

(21) Appl. No.: **29/245,626**

(22) Filed: **Dec. 28, 2005**

(30) **Foreign Application Priority Data**

Aug. 12, 2005 (JP) 2005-023581

(51) **LOC (8) Cl.** **13-03**

(52) **U.S. Cl.** **D13/147**

(58) **Field of Classification Search** D13/133, D13/146–147, 154, 184, 199; D14/356, 363, D14/365, 385, 433; 439/350, 607–610, 677, 439/680–682

See application file for complete search history.
